UNITED STATES PATENT OFFICE.

VINCENT BARTON, OF WICKERSHAM, WASHINGTON.

PUNCH.

Application filed March 23, 1923. Serial No. 627,201.

To all whom it may concern:

Be it known that I, VINCENT BARTON, a citizen of the United States, residing at Wickersham, in the county of Whatcom and

5 State of Washington, have invented certain new and useful Improvements in Punches, of which the following is a specification.

This invention relates to punch devices adapted to form holes in metal bodies such 10 as straps, plates and the like, and has for one of its objects to simplify and improve the construction and increase the efficiency and utility of devices of this character.

Another object of the invention is to provide 15 a device of this character including a yieldably supported punch member having means whereby the yieldable supporting means may be held in compressed position while the parts are being assembled.

20 With these and other objects in view the invention consists in certain novel features of construction as hereinafter shown and described and then specifically pointed out in the claim, and in the drawings illustrative 25 of the preferred embodiment of the invention—

Figure 1 is a side elevation, partly in section, of the improved device.

Figure 2 is a section on the line 2—2 of 30 Figure 1.

Figure 3 is a vertical section on the line 3—3 of Figure 1, looking in the direction of the arrow.

Figure 4 is a rear elevation illustrating 35 a modification of the construction.

The improved device comprises a body or stock formed with lower or base portion 10 for supporting the die, and upper or punch carrying portion 11, the upper face of the 40 portion 10 and lower face of the punch carrying portion 11 being in spaced relation as shown.

The body may be formed open at the front and rear and at one side, as shown in Figures 45 1 and 2, or open at the front and rear only and closed at both ends, as shown in Figure 4.

Formed within the upper portion 11 of the body is a recess or cavity 12 communicating 50 with the upper face of the portion 11 by a guideway 13, and laterally enlarged at the lower end to form an annular seat 14 to receive an annular stop member 15, the latter held in place by clamp screws 16. The bore 55 of the stop member 15 corresponds to the guideway 13 and the bore of the member 15.

An outwardly directed stop flange 18 is carried by the punch 17 and bears normally against the upper end of the recess 12, as shown.

At its lower end the punch 17 is reduced as shown at 19 and constitutes the metal penetrating portion, the lower end of the portion 19 being preferably provided with a centering point 20.

A spring 21 surrounds the body of the punch 17 within the recess 12 and bears against the stops 15 and 18, and thus exerts its force to maintain the punch normally in its upper and withdrawn position.

The lower or base portion 10 of the body is provided with a relatively large opening indicated at 22, with the lower portion tapered or bevelled and the upper portion cylindrical, and fitting within this opening 75 is a die member 23 having a portion of its outer periphery tapered and a portion cylindrical to correspond to the tapered and cylindrical part of the opening 13, as shown in Figures 1, 3 and 4.

The portion 10 of the body is formed with an upwardly extending rib 24 having a plurality of threaded apertures to receive clamp screws 25 engaging the cylindrical portion of the die and thus holding it in position.

The die 23 is provided with an opening 23' corresponding to the portion 19 of the punch, and connected with a downwardly diverging or tapered portion 25', to insure 90 the free discharge of the fillets punched out at each operation of the device.

A stripping member 27 is disposed between the body portions 10 and 11 and slotted to permit the punch to pass. The 95 member 28 is formed with an upstanding portion 28 slotted as shown at 29 to receive a holding screw 30, the slot permitting the stripper to be adjusted to correspond to the thickness of the object to be punched.

Tapped through one of the sides of the portion 11 of the body is a stop screw 31 adapted to be inserted at its inner end into the path of the spring 21 and hold the latter compressed while the stop member 15 is being installed.

The improved device is simple in construction, can be manufactured of any required size or capacity to receive any required size of punch.

The preferred embodiment of the invention is disclosed in the drawings and set

forth in the specification, but it will be understood that modifications within the scope of the claimed invention may be made in the construction without departing from the principle of the invention or sacrificing any of its advantages.

Having thus described the invention what is claimed as new is:

In a device of the class described a body of upper and lower portions in spaced relation, said upper portion having an internal recess and alining guideways communicating

with the recess, a punch operating through the guideways and having a stop flange operating in the recess, a spring within the recess and bearing against the stop flange, and a threaded pin operating through the body and adapted to be projected into the path of the spring to hold the same compressed while the punch is being installed.

In testimony whereof, I affix my signature hereto.

VINCENT BARTON.
